TURBINE PUMP

John R. Betts, Kearney, Nebr.

Application September 27, 1937, Serial No. 165,817

6 Claims. (Cl. 103—90)

My invention relates to turbine pumps, one of its objects being the provision of a rotary pump having a peripheral bearing instead of a bearing at the axis of the cylindrical wall.

5 Another of my objects is the provision of a rotary pump having a peripheral impeller in combination with a peripheral bearing.

Another object is the provision of a rotary pump having a peripheral bearing together with 10 impellers at both the bearing and on the inner side thereof.

Another object which I have in view is the provision of a rotary pump with a peripheral bearing designed for the forcible ejection of sand and 15 other abrasives therefrom.

It is also my object to provide a rotary pump designed for water lubrication exclusively to avoid tainting of the water.

Another object which I have in view is the 20 provision of a rotary pump with means for deflecting the spinning current of water into an upward direction.

Another of my objects is the provision of a rotary pump having an impeller with a peripheral bearing in the well casing and having an antispinner at the axis of the impeller for deflecting in an upward direction the spinning stream of water.

Another object is the provision of a rotary 30 pump having a casing and an impeller and an antispinner so designed and arranged that the impeller and the antispinner may be withdrawn without disturbing the well casing.

Another object is the provision of a rotary 35 pump including a well casing, a shaft suspended in the well casing, a shroud ring spaced from both the shaft and the well casing, and impellers at both the inner and outer peripheries of the shroud ring.

40 Having in view these objects and others which will be pointed out in the following description, I will now refer to the drawings, in which

Figure 1 is a sectional view of the well with the well casing of my turbine pump installed 45 therein.

Figure 2 is a view in much enlarged scale showing in section the meeting edges of two lengths of the well casing and showing also the bearings and impeller.

50 Figure 3 is a view in elevation showing the coupling joining two lengths of shafting and showing also the shroud ring and the tire in their relation to an impeller, a portion at the left in the figure being broken away.

55 Figure 4 is a sectional view on the line 4—4

of Figure 3 and looking in the direction of the arrows.

Figure 5 is a perspective view of a tire.

Figure 6 is a view in perspective showing an independent bearing member for coupling two 5 lengths of the shafting together without using impeller blades at the shaft joint.

Figure 7 is a perspective view in section showing the use of an antispinner with my impeller.

Figure 8 is a view in longitudinal section 10 through the casing and showing the relation of the antispinner to the impeller and casing.

Figure 9 is a sectional view on the line 9—9 of Figure 8.

Figure 10 is a transverse sectional view of a 15 fragment of the antispinner and the casing and showing particularly the position of the parts at one point in their assemblage.

Figure 11 is a vertical sectional view of the 20 lower end portion of the casing.

The well is shown at 10 in Figure 1, the well being provided with a suitable lining or with no lining at all depending on the nature of the soil in which the well is sunk. The numeral 10 therefore designates merely the peripheral wall of the 25 well. The well casing consists of a plurality of lengths 11 which are joined together by couplings 12, these couplings being in the nature of screw threaded sleeves as best shown in Figure 2. The lengths 11 are uniform in all respects, 30 my preference being for lengths of pipe which are from eight to ten feet long. The lengths 11 when joined together by the couplings 12 constitute the well casing through which the water is drawn. Centrally positioned inside the well casing is a shaft 13 for driving the impellers, the shaft 13 being in lengths which are equal to the lengths 11. Above the surface of the soil is a 35 motor 14 of any suitable type or form.

As shown in Figure 2 the edges of the casing 40 lengths 11 abut against each other and their end portions are joined together by means of a coupling 12, both the coupling and the end portions of the lengths 11 being screw threaded. The same thing is true of the shaft 13, the end portions of the shaft lengths being secured together by the hubs 15. Additional securing means is provided with the nuts 16 above and below the hub 15 with the spring washers 17 interposed between the nuts 16 and the ends of the hub 15. 45

Inside each length 11 and at the lower extremity thereof, is a bearing member 18 in the form of a liner. These liners are preferably made from such a non-rusting material as stainless steel or manganese bronze which is shrunk 50

into the section 11 and then machined to provide a perfect bore. The upper and lower edges of the bearing members 18 are bevelled and rounded as shown in Figure 2 for their Venturi effect during the operation of the pump. Secured to the hub 15 is a shroud ring 19 having thereon a tire 20 which is preferably made from an organic non-metallic material such as hard rubber, lignum vitae, impregnated maple or any other suitable material for which water is a lubricant. The shroud ring 19 is provided with flanges at its top and bottom for firmly holding the tire 20 as best shown in Figure 4. The tire 20 is provided with spirally arranged grooves 21 for both functioning as impellers and for carrying the water lubricant to all parts of the bearings to thus avoid the accumulation of sand and the unnecessary cutting out of the parts of the bearings. The water passing through these grooves 21 forms a very thin film of water over the entire contacting surface of the bearings to provide adequate lubrication.

Connecting the hub 15 and the shroud ring 19 are the impeller blades 22 which are formed integral with both the hub 15 and the shroud ring 19. It is the rotation of these impeller blades about the axis of the shaft 13 which carries the water upwardly. The pitch of these impeller blades depends to some extent on the local conditions and especially as relates to the rate of flow which is possible to get from the particular well. The grooves 21, however, should have substantially the same pitch as that of the impeller blades 22.

35 The pump may be formed by the use of an impeller and shroud at every coupling 12. By means of this construction the water is lifted from the bottom end of one length of casing 11 to the bottom end of the next length where it is picked up by the next above impeller and carried upwardly. In some cases, however, it may be desirable to provide a coupling for two shaft lengths and to associate that particular coupling with a bearing but not with an impeller. In such cases 45 I employ the device shown in Figure 6 in which the hub is shown at 23, this being connected through spokes 24 to the shroud ring 25. The shroud ring 25 is identical in form with that of the shroud ring 19 so that it receives the same 50 tires 20 as does the shroud ring 19.

Depending on the speed of rotation of the impeller and the pitch of the impeller blades, the device will sometimes set up a spinning motion in the column of water so that much of the energy is wasted in imparting a circular movement to the water instead of movement in an upward direction. When this condition is encountered it is necessary to provide means for straightening out the column of water. I therefore provide an antispanner which may be employed whenever the conditions warrant or necessitate its use.

60 As shown in Figures 7 to 10 inclusive, the antispanner includes a sleeve 26 which loosely surrounds the shaft 13. Integral with the sleeve 65 26 is a plurality of blades 27 having their bottom edges curved at 27' into the whirling stream of water from the impeller and having their outer edges curved in the opposite direction. The outer edges of the blades 27 terminate short of the casing wall 11 but the supplemental blades 28 are secured to the blades 27 with their outer edges in intimate contact with the inner wall of the casing. The supplemental blades 28 should 70 be quite flexible and resilient but at the same time

they should be sufficiently stiff to meet the demands on them. They are curved as best shown in Figure 10 in the direction away from the direction of movement of the whirling stream of water. The casing 11 is provided with ribs 29 which serve as abutments for the supplemental blades 28. This permits freedom of rearward rotation of the antispanner but only limited forward rotation as the antispanner will be held stationary when the outer edges of the supplemental blades 28 abut against the ribs 29 as shown in the dotted line position in Figure 10. The reverse rotation of the antispanner will cause the supplemental blades 28 to ride over the ribs 29. During the operation of the impeller the water is picked up by the lower end portions 27' of the blades 27 and is then prevented by the supplemental blades 28 from spinning while passing upwardly through the antispanner. The sleeve 26 terminates at its lower extremity in a collar 30 35 which is adapted to rest on the hub 15. The collar 30 is preferably formed of two metallic discs on opposite sides of a rubber disc.

The supplemental blades 28 must be designed for convenience in assemblage and disassembly of the pump. They must be so formed as to not only contact the inner surface of the casing wall but they must be adapted to pass the bearing members 18 during assemblage or disassembly. The shaft 13 is in sections or 40 lengths and the impellers are secured to the shaft at the joints between the shaft lengths. The pump is assembled by adding lengths of shafting with impellers and by gradually lowering the impellers with the shafting in the casing while adding lengths. When antispanners are employed the antispanners should be added above the impellers in the manner shown in Figure 8. This naturally demands that the antispanners be so designed that they will readily pass through the bearing members 18 which have a smaller diameter than the effective diameter of the antispanners. As best shown in Figure 8, the supplemental blades 28 have their upper edges cut away at 31 and their lower edges at 32, the cuts making a long slope with reference to the blades. Since these blades are flexible and resilient, downward pressure during assemblage of the pump as in the Figure 8 position will cause the blades 28 to 45 buckle as shown in full lines in Figure 10 and into the position where further downward movement is within the restricted diameter of the bearing members 18 until the lower end of the bearing member is reached when the blades 28 will snap back into their normal position against the inner peripheral wall of the casing. The same thing is true when the pump must be disassembled by drawing the impellers and shafting upwardly through the well casing 11. At such 50 times the sloping edges 31 will bear against the lower edges of the bearing members 18 so that they will buckle to permit the antispanner to pass through the bearing members 18.

As shown in Figures 1 and 11, the lower end 65 of the well casing is in frustoconical form with the lower opening of larger diameter than that of the well casing. During assemblage or disassembly it is possible that one of the joints in the shafting 13 may be released to drop a portion 70 of the shafting with the impellers down to the bottom of the well. Since the mouth of the casing is usually above the bottom of the well, such an accident may cause an impeller to fall to a position below the well casing and out of reach 75

of any tools which may be applied. For this reason it is desirable that the lower end of the well casing be provided with the bar 33 or with any other desired stop member which will not 5 obstruct the flow of water but which will prevent the passage of falling portions of the pump.

The outstanding characteristic of the present invention is the peripheral position of the bearing in the well casing. In the prior devices the 10 bearings are centrally positioned but this makes it difficult to preserve the vertical alignment of the bearings. Because of the very large bearing surfaces the shafting will tend to maintain its vertical position at the center line of the well 15 casing. In the manufacture of my pump the material for the bearing members 18 is forced into the lower ends of the casing lengths 11 and they are then machined for accurate but close fit with the tires 20. These sections are then carried 20 to the job where they may readily be assembled in the field without the use of special tools.

The bearing members 18 and 20 are made from different materials but which are both readily lubricated by the film of water. No lubricant 25 other than water is employed and this avoids the tainting of water when the pump is designed to supply water for household use. The materials used in the bearing members are not only thoroughly lubricated by the water but they are of 30 such a nature that very little wear can occur between them. Should the bearings become loose, it is only necessary to raise or lower the entire shafting with the impellers in order to bring the bearing members 20 into contact with 35 the bearing members 18 at a slightly higher or lower position.

Another great advantage of my pump resides in the construction which permits the removal of the shafting and impellers from the 40 well casing without incurring the heavy labor costs of removing the entire casing from the well. This shafting may be drawn upwardly and it may be disassembled if its length is too great. Any desired repairs or replacements may be made and 45 the shafting with the impellers may then be again inserted into the well casing without otherwise disturbing the well casing. This is true whether the pump is employed with or without the antispinner. As before described, the antispinner 50 is so constructed that it operates against the inner peripheral walls of the lengths 11 of the casing but at the same time it may pass the bearing members 18 in either their upward or downward movement in the well casing.

55 Prior centrifugal pumps have shafts which rotate in bearings, the bearings being located at the top and bottom and at intermediate points on the shaft. Of necessity these bearings must be maintained in precise alignment. The impellers as a rule are given sufficient clearance 60 with the casing wall to compensate for irregularities in alignment of the bearings. Instead of the prior arrangements, I dispense with special bearings and so design the impellers with relation to 65 the well casing that no bearings other than the impellers are needed, the dependence being solely on the impellers as bearings. The impellers ride snugly against the sleeves and not only maintain all parts of the shaft in vertical alignment 70 but they prevent the irregular stray currents of water at the peripheries of the impellers. Except for the grooves 21 the bearings for the impellers are sealed and these grooves together with the seal insure that the passage of water at the periphery is under control. At the same time, the 75

sand is ejected and all parts of the bearings are kept wet so that the impellers ride smoothly on their films of water. The abrasive action on the bearings is negligible for this reason but when a part becomes worn it is only necessary to raise 5 or lower the shaft with the impellers only a slight distance in order to bring new bearing surfaces into contact.

Having thus described my invention in such full, clear, and exact terms that its construction and operation will be readily understood by others skilled in the art to which it pertains, what I claim as new and desire to secure by Letters Patent of the United States is:

1. A rotary water pump including a well casing, 15 a rotatable shaft centrally suspended in said well casing, an impeller member secured to said shaft, a flanged rim surrounding said impeller member, a tire surrounding said rim and secured thereto between said flanges, said tire being of an organic, 20 non-metallic material for which water is an effective lubricant, and being of a size to have a peripheral bearing with the interior of said casing, and means for driving said shaft at a high speed.

2. A rotary water pump including a well casing, 25 a rotatable shaft centrally suspended in said well casing, an impeller member secured to said shaft, a tire surrounding said impeller and secured thereto, said tire being of an organic non-metallic 30 material for which water is an effective lubricant, a sleeve of non-corrosive metal secured inside of said casing surrounding said tire, said sleeve having an internal diameter substantially equal to the external diameter of said tire, and means for driving said shaft at a high speed.

3. A rotary water pump including a well casing, 40 a rotatable shaft centrally suspended in said well casing, an impeller member secured to said shaft, a rim surrounding said impeller member, a tire 45 surrounding said rim and secured thereto, said tire being of an organic, non-metallic material for which water is an effective lubricant, and being of a size to have a peripheral bearing with the interior of said casing, said tire further being provided with diagonally extending grooves in the exterior surface thereof to force water between said tire and said casing upon rotation of said impeller, and means for driving said shaft at a high speed.

4. A rotary pump including a well casing, a 50 rotatable shaft centrally suspended in said well casing, an impeller member secured to said shaft and comprising a plurality of helically extending blades and a surrounding rim, a tire surrounding 55 said impeller rim and secured thereto, said tire being of an organic non-metallic material capable of being effectively lubricated by the liquid being pumped, and a bearing member in the form of a sleeve secured inside of said casing and having an 60 internal diameter substantially equal to the external diameter of said tire, said tire being provided with grooves in the outer surface thereof extending diagonally in the same direction and having substantially the same pitch as said blades, 65 said grooves being of sufficient depth to force the liquid being pumped into the space between said tire and said bearing member without weakening said tire.

5. A rotary pump including a well casing comprising a plurality of casing sections, a rotatable shaft centrally suspended in said casing, said shaft being formed of a plurality of sections equal in number and in length to said casing sections, a plurality of impeller members secured to said 70

shaft adjacent the ends of said shaft sections and each comprising a surrounding rim, a tire surrounding each impeller rim and secured thereto, said tires being of an organic non-metallic material capable of being effectively lubricated by the liquid being pumped, sleeve bearing members secured internally of said casing adjacent the ends of said casing sections, one of said sleeve bearing members being located adjacent each of said impeller members in bearing engagement with the tire secured thereto, each of said tires being provided with diagonally extending grooves in the exterior surface thereof to force water between said tire and its associated sleeve bearing member, and a plurality of means for reducing the spinning motion of the water above said impellers, each of said means comprising a sleeve loosely surrounding said shaft and a plurality of radial blades secured to said sleeve, said blades having flexible extensions to facilitate the passage of the blades

over said sleeve bearing members, said flexible extensions non-radially engaging the interior of the casing and said casing being provided with projections engaging said flexible extensions to prevent rotation in any but one direction.

6. A rotary water pump including a well casing, a rotatable shaft centrally suspended in said well casing, an impeller member secured to said shaft, a rim surrounding said impeller member, a tire surrounding said rim and secured thereto, said tire being of a material for which water is an effective lubricant, and being of a size to have a peripheral bearing with the interior of said casing, said tire further being provided with diagonally extending grooves in the exterior surface thereof to force water between said tire and said casing upon rotation of said impeller, and means for driving said shaft at a high speed.

JOHN R. BETTS. 20
